UNITED STATES PATENT OFFICE.

JOSEPH L. BALLASH, OF CLEVELAND, OHIO, ASSIGNOR TO THE STERLING GRINDING WHEEL COMPANY, OF TIFFIN, OHIO, A CORPORATION OF OHIO.

SECTIONAL GRINDING WHEEL.

Application filed March 2, 1927. Serial No. 171,963.

This invention relates to sectional grinding wheels being more particularly directed to that type of wheel in which a side face is used for grinding, and has for an object to provide such a wheel made up of a series of interfitting sections.

A further object of the invention is to provide a sectional grinding wheel in which the blocks of abrasive material forming the sections of the wheel are so joined together that articles being ground in passage over the joints between the sections will not be damaged and will not damage the wheel.

A further object is to provide a sectional grinding wheel in which the segmental blocks of abrasive material forming the sections of the wheel are so fitted together as to automatically compensate for slight variations in the dimensions of the blocks from the theoretically exact form so that the blocks may be used as they come from the molds without finishing operations.

With the above and other objects in view, the invention may be said to comprise the structure as illustrated in the accompanying drawing hereinafter described and particularly set forth in the appended claims, together with such variations and modifications thereof as will be apparent to one skilled in the art to which the invention appertains.

Reference should be had to the accompanying drawings forming a part of this specification, in which:

Fig. 1 is a plan view of a sectional grinding wheel embodying my invention;

Fig. 2 is a sectional view taken on the line indicated at 2-2 in Fig. 1; and

Fig. 3 is a perspective view of one of the blocks.

Referring to the accompanying drawing, the grinding wheel is annular in form and is built up of a series of identical blocks 1, each of which has an inner face 2 of cylindrical curvature and an outer face 3 conforming to a concentric cylindrical surface. One end face of the block 1 is provided along the inner and outer sides thereof with flat portions 4 which lie in a plane which is spaced from the axis of curvature of the inner and outer faces 2 and 3; or, in other words, at an angle to radial planes. A transversely arcuate groove 5 of uniform curvature and depth extends across the end of the block between the flat portions 4 and substantially midway between the inner and outer sides 2 and 3.

The opposite end of the block is provided with flat portions 6 in a plane which converges inwardly toward the plane of the flat portions 4 of the opposite end and which is also disposed at an angle to radial planes 60 normal to the inner and outer surfaces 2 and 3. Between the flat portions 6, an arcuate rib 7 extends across the end of the block which is of a size to fit within the arcuate groove of an adjacent block.

When the sections are interfitted as shown in Fig. 1, the outer surfaces 3 of the sections form the substantially cylindrical periphery of the wheel, and the inner surfaces 2 form the substantially cylindrical hub opening of 70 the wheel. The ribs 7 are of a height slightly greater than the depth of the grooves 5 so that there is a slight clearance between the adjacent flat portions 4 and 6 of the blocks, and since the grooves and ribs are of transversely arcuate form, they provide a rocking adapter bearing between the adjoining sections, permitting the sections to rock one upon the other during assembly so that slight inaccuracies in the dimensions of the blocks 80 will be compensated for. The sections may be taken directly from a mold and fitted together in a suitable form or chuck and then secured upon a suitable supporting disk 9. If the compensation provided for by the 85 rocking bearings between the sections is insufficient, one or more canvas shims, as indicated at 8 in Fig. 1, may be inserted in the grooves 5 to spread the sections.

When the grinding wheel is in use, the 90 joints which extend at an angle to radii of the face of the wheel against which the article being ground engages, will remain at an angle to the face of the article and pass endwise beneath the article and along the 95 length thereof during rotation of the wheel so that neither the grinding wheel nor article being ground will be damaged.

Having thus described my invention, I claim:

1. A sectional grinding wheel formed of a series of interfitting segmental blocks, the contiguous faces of each pair of contiguous blocks having an adapter bearing formed by a transversely concave groove in one block extending across the same intermediate the inner and outer edges and a correspondingly positioned rib on the other block adapted to fit and have a rocking bearing in the groove, there being a clearance between the adjacent 110

faces of the blocks between the rib and groove and inner and outer edges of said faces.

2. A sectional grinding wheel formed of a series of interfitting segmental blocks, the 5 contiguous faces of each pair of contiguous blocks being disposed at an angle to radii of said wheel and having an adapter bearing formed by a transversely concave groove in one block extending across the same intermediate the inner and outer edges and a correspondingly positioned rib on the other block adapted to fit and have a rocking bearing in the groove, there being a clearance between the adjacent faces of the blocks between the 10 rib and groove and inner and outer edges of said faces.

3. An abrasive block adapted to form one of a series of identical sections of an annular grinding wheel and having inner and outer concentric faces of uniform curvature and 20 inwardly converging end faces inclined with respect to planes normal to said inner and outer faces, one of said end faces having a transversely arcuate groove extending across the same intermediate said inner and outer faces, and the other of said end faces having a transversely arcuate rib adapted to fit in the groove of an identical block.

In testimony whereof, I hereunto affix my signature.

JOSEPH L. BALLASH.
